UNITED STATES PATENT OFFICE.

KARL M. ROSSI, OF SCHENECTADY, NEW YORK.

COMBINED GUARD AND HANGER FOR PULLEYS.

1,405,008.

Specification of Letters Patent. Patented Jan. 31, 1922.

Application filed January 11, 1921. Serial No. 436,584.

To all whom it may concern:

Be it known that I, KARL M. Rossi, a citizen of the United States, residing at Schenectady, county of Schenectady, State 5 of New York, have invented certain new and useful Improvements in Combined Guards and Hangers for Pulleys, of which the following is a specification.

The present invention relates to combined 10 guards and hangers for pulleys, and one specific application is their use in clothes line pulleys. The object of the invention is to provide a device of the character described of improved construction.

15 For a description of what I believe to be novel and my invention, attention is directed to the accompanying description and the claims appended thereto.

In the drawing, which illustrates one of 20 the embodiments of my invention, Fig. 1 is a view in side elevation of a clothes line pulley; Fig. 2 is a detail exploded view of one of the joints between the guard and hanger, and Figs. 3 and 4 are detail views 25 showing a reinforcing piece for the hanger.

5 indicates a sheave pulley which may be of any suitable construction. It comprises a rim 6 which is concave in cross section as is usual and a number of spokes 7. By preference the wheel and its spokes are made of sheet steel because such a construction is light in weight and not easily broken even by rough handling. The parts can also be easily coated with a durable material to prevent 30 rusting.

In a device of this kind it is of the greatest importance to provide a rigid guard and hanger and one which is light in weight and at the same time possesses great strength. 40 That is to say, they must be stiff enough to prevent the wheel from rubbing on them when in use. This also means a rigid relation between the guard and hanger if best results are to be obtained. To this end the 45 guard 8 is made of a strip of sheet steel which completely encircles the wheel and has overlapping ends to form a joint, the latter coinciding with the region of the wheel axis. In order to increase the strength of the 50 guard it is provided with at least one, and preferably two ribs 9, throughout its length. The rib or ribs may advantageously be formed by dies before the strip is bent to enclose the wheel. It is necessary to interlock 55 the overlapping ends of the guard in order to prevent distortion or racking at the

joint. To attain this result, the ribs at one end of the guard, as indicated at 10, are made just enough smaller than those at the opposite ends so that when the ends of the 60 guard are overlapped the smaller ribs will snugly fit into the recesses of the larger ribs and the main bodies will be in firm contact.

Referring now to the hanger, it is also important that it shall be strong and also be securely fastened to the guard so that all angular movement of one with respect to the other about the wheel axis is prevented. Also that the joints between the guard and 70 hanger be of such a character and the hanger of such a nature that the wheel cannot, when in use, distort the hanger and cause rubbing.

To this end the U-shaped hanger 11 is also 75 made of sheet steel and is provided with one or more ribs 12 extending lengthwise thereof. These ribs are purposely stopped just short of the ends so as to provide a clear space for the formation of one and preferably, two cross ribs 13. The cross ribs are of such size that when the guard and hanger are assembled they will fit or nest with the rib or ribs 9 on the uppermost part of the guard and the body will firmly contact with 80 the adjacent body of the hanger. Stated another way, the leg has a projection on one face and a recess on the other which recess is just large enough to receive and snugly contain the aligned projection on the guard. 90

On the opposite leg of the hanger the construction is the same and the cross-ribs on the hanger snugly fit over the lengthwise ribs on the guard. After the parts are assembled with the wheel in place a pivot 14 95 is slipped into place through properly registering holes in the guard and hanger, after which it is riveted over at both ends to form retaining heads. The pivot securely holds the parts from spreading in an axial direction and the interlocking ribs on the guard hold the overlapping ends thereof in such manner as to prevent the guard from buckling or the ends from being displaced laterally. The pivot also holds the cross ribs on 100 the hanger in firm engagement with the ribs on the guard with the result that there can be no angular movement of one part on the other, or bending of the hanger which would allow the wheel to rub.

I may and preferably do turn the ends of the hanger inward as indicated at 15 and

cause them to make a snug fit with the outer edges of the guard. The inturned edges of the hanger in addition to preventing side-wise displacement of the overlapping ends of 5 the guard serve to relieve the strain on the pivot to a certain extent when the pulley is in use and the hanger is subjected to heavy tension as it frequently is when the clothes line is heavily loaded or the line shrinks, 10 or both.

To prevent wear on the outer end of the hanger a reinforcing piece 16 is provided which is set into a narrow recess or groove formed in the hanger at the bend. This is 15 held in place by projections or tongues 17 formed by a punching or cutting operation.

In accordance with the provisions of the Patent Statutes, I have described the principle of operation of my invention, together 20 with the apparatus which I now consider to represent the best embodiment thereof, but I desire to have it understood that the apparatus shown is only illustrative and that the invention may be carried out by other 25 means.

What I claim as new and desire to secure by Letters Patent of the United States, is:—

1. A pulley, a guard which encloses it and has overlapping ends, said overlapping ends 30 having projections, a projection on one of said ends fitting into a recess formed by a projection on the other end, and means for holding the projection in the recess.

2. A pulley, a guard which encloses the 35 wheel and has overlapping ends, said guard including the overlapping ends having projecting ribs which extend lengthwise of the guard, one of said ribs fitting into the recess formed by the other rib, and means for holding 40 the rib in said recess.

3. A pulley, a guard which encloses it and has a pair of overlapping ends, one of said 45 ends having projections which are separated from each other, the other having recesses which are similarly separated and are arranged to receive the projections, a hanger having ends which are connected to the guard, and means for pivotally supporting the pulley and uniting the guard and hanger.

50 4. A pulley, a guard which encloses the wheel and has overlapping ends, said overlapping ends having parallel projecting strengthening ribs which extend lengthwise of the guard, the ribs on one end fitting into the recesses formed by the other ribs, means for holding the ribs in said recesses, and a hanger, the ends of which have transverse, parallel recesses to receive said ribs.

55 5. A pulley, a guard which encloses it and

has a pair of overlapping ends, one of said 60 ends having a projection and the other end a recess, said projection fitting into the recess to form a joint, a hanger having two legs, co-operating projections and recesses on the guard and legs to unite the parts, and a 65 pivot for the pulley.

6. A pulley, a guard which encloses it and has overlapping ends, projections on both 70 of said ends one of which fits into the other, a second projection on the side of the guard opposite said ends, a hanger for the pulley the legs of which have projections, the recesses formed by said projections fitting over the projections on the guard, and means for holding said projections in interlocking engagement.

7. A pulley, a guard which encloses it and has overlapping ends, interlocking ribs on 80 said ends, ribs on the side of the guard opposite the joint, a hanger having legs, ribs formed in the legs which extend parallel with those on the guard and interlock with them, and a pivot for the wheel that also holds said ribs in interlocking engagement.

8. A pulley, a guard which encloses it and has overlapping ends, means for holding 85 said ends against side-wise displacement, a hanger having legs which straddle the wheel, turned over ends for the legs which engage one side of the guard and assist in transmitting strains from the wheel to the hanger, and a pivot for the wheel which is seated in the guard.

9. A pulley, a sheet metal guard which encloses it, and has overlapping ends, said 95 guard being ribbed from end to end, the ribs on one end fitting into the recesses formed by the ribs on the other end, a hanger which has lengthwise ribs and also cross ribs, the cross ribs fitting over the ribs on the guard, 100 and a pivot for the wheel that also holds the rings of the guard and hanger in interlocking engagement.

10. A wheel having a guard which encloses it, a U-shaped hanger having a recess 105 at the bend, a reinforcing piece which is located in the recess, and projections on the hanger which engage the ends of the piece to hold it in place.

11. A wheel having a guard which encloses it, a U-shaped hanger, a reinforcing piece which is located in the bend of the U, and a pair of projections on one part which engage the other to hold said piece in place.

In witness whereof, I have hereunto set 115 my hand this 8th day of January, 1921.

KARL M. ROSSI.
